UNITED STATES PATENT OFFICE

WILLIAM J. SMITH, OF MOORE, MONTANA

TRASH-CLEARER ATTACHMENT FOR CULTIVATORS

Application filed March 19, 1928. Serial No. 262,971.

The present invention relates to a duck foot cultivator cleaner and is a mechanical device designed for use on a duck foot cultivator and has for its prime object to provide means to 5 keep dirt and field trash from accumulating and clogging in said cultivator, thus widening its usages.

A still further important object of the invention resides in the provision of a device 10 of this nature which is exceedingly simple in its construction, strong and durable, and thoroughly efficient and reliable in use.

With the above and numerous other objects in view as will appear as the description proceeds, the invention resides in certain novel features of construction, and in the combination and arrangement of parts as will be hereinafter more fully described and claimed.

In the drawings:

20 Figure 1 is a side elevation of a cultivator embodying the features of my invention,

Figure 2 is a top plan view thereof,

Figure 3 is an enlarged detail section through the picker wheel,

25 Figure 4 is a detail section taken substantially on the line 4—4 of Figure 2,

Figure 5 is an enlarged detail section through one of the tensioning devices,

30 Figure 6 is a perspective view of the picker wheel beam, and

Figure 7 is a perspective view of another form of blade for the picker wheel.

Referring to the drawing in detail it will be seen that the numeral 1 denotes the duck 35 foot cultivator beam which has a shank 2 pivoted to the rear end thereof and depending downwardly and having fixed to its bottom end a cultivator shovel 3. A tensioning spring 4 is anchored at one end to an intermediate 40 portion of the shank 2 as at 5 and at its other end to an intermediate portion of the beam 1 as at 6 and urges the shovel forwardly in the usual well known manner. All the parts thus far described are of conventional construction 45 and well known in the art and have been illus-

trated herein for the purpose of exemplifying the utility of my improved structural features.

The letter A denotes generally a rotary picker wheel which includes a hub structure 50 7 and a plurality of spoke blade receiving plant sockets 8 for receiving blades 9 or 10.

The letter B denotes the picker wheel beam which includes an elongated straight body 11 having an offset pintle 12 at one end and 55 an oppositely offset axle shaft 14 at the other end on which is rotatable the hub 7 of the picker wheel A. Intermediate the ends of the elongated body 11 of the beam B there is provided an apertured ear 15. The letter C denotes a casting which is attached to the beam 1 by means of suitable fastening elements such as bolts 16 and has a bearing for rockably receiving the pintle 12. An arm 17 is rockably mounted on the beam 1 by means of a 60 bolt 18 and has an offset apertured ear 19 at its upper end for slidably receiving a rod 20, the lower end of which is pivotally engaged with the apertured ears 15 as at 21.

A stop 22 is provided on the rod 20 and a 65 spring 23 is disposed about this rod impinging against the top 22 and the apertured ear 19 to urge the beam B to swing downwardly with the picker wheel in engagement with the ground, the ground line being indicated by 70 the letter G in Figure 1. The blades 10 may be substituted for the blades 9 and have detachable plates 11 adjacent the ends thereof. Of course the blades 9 may be provided with 75 these blades 10. These plates are used in exceptionally loose soil and aids materially in keeping the cultivator clean.

The picker wheel A rotates ahead of the duck foot shovel 3 and continuously moves loose dirt and trash over the duck foot shovel 85 and past the shovel shank, thereby preventing said dirt and trash from accumulating and clogging the cultivator. It will be seen that the picker wheel is disposed in advance of the shovel and slightly to one side of the 90

apex of said shovel. The presser spring 23 maintains a continuous pressure on the beam B thereby insuring positive traction to the picker wheel which takes its traction from the ground in which it runs.

5 At the same time this spring allows the wheel to raise over solid obstruction such as rock etc., often encountered in actual practice and furthermore the spring causes the 10 raising of the shovel when the picker wheel encounters an object so that the shovel will not strike the obstacle. The casting C is adjustable since the bolt 16 may be loosened so as to slide the casting forwardly or rearwardly.

This adjustment allows the picker wheel and beam to be moved forward and backward for adjustment as the case may require at the same time allowing it to raise and lower.

20 One of these attachments is to be associated with each beam of the cultivator to keep it free of trash and dirt.

The uses of a duck foot cultivator without this device are limited but with it the cultivator may be used in trashy fields heretofore shunned by users of the duck beam foot cultivator. It will also be seen that by the prevention of clogging the draft is materially lightened.

30 It is thought that the construction, utility, operation and advantages of this invention will now be quite apparent to those skilled in this art without a more detailed description thereof. The present embodiment of 35 the invention has been disclosed in detail merely by way of example since in actual practice it attains the features of advantage enumerated as desirable in the statement of the invention and the above description.

40 It will be apparent that changes in the details of construction, and in the combination and arrangement of parts may be resorted to without departing from the spirit or scope of the invention as hereinafter 45 claimed or sacrificing any of its advantages.

Having thus described my invention, what I claim as new is:

1. A trash clearer for cultivator shovels comprising a rotary picker wheel, and means 50 for mounting the wheel in advance of the shovel and toward one side of the point thereof, said means consisting of a rod bent laterally at its opposite ends and in opposite directions, one end of the rod being journaled 55 to the cultivator frame, and said wheel being journaled on its opposite end, and tensional means between the frame and the rod for urging the wheel against the ground.

60 2. A trash clearer for cultivator shovels comprising a rotary picker wheel, and means for mounting the wheel in advance of the shovel and toward one side of the point thereof, said means consisting of a rod bent laterally at its opposite ends and in opposite 65 directions, one end of the rod being jour-

naled to the cultivator frame, and said wheel being journaled on its opposite end and tensional means between the frame and the rod for urging the wheel against the ground, said tensioning means consisting of a rod pivotally connected at one end to the aforementioned rod, guide means on the cultivator frame, and spring means interposed between the first mentioned rod and the said guide means.

70 In testimony whereof I affix my signature.
75 WILLIAM J. SMITH.
